UNITED STATES PATENT OFFICE

120,649

DESIGN FOR A COMBINED DISPLAY AND DISPENSING CARTON

Edward J. Novak, Chicago, Ill.

Application March 20, 1940, Serial No. 91,100

Term of patent 7 years

To all whom it may concern:

Be it known that I, Edward J. Novak, a citizen of the United States, residing at Chicago, in the county of Cook and State of Illinois, have invented a new, original, and ornamental Design for Combined Display and Dispensing Cartons, of which the following is a specification, reference being had to the accompanying drawing, forming a part thereof.

In the drawing:

I claim:

The ornamental design for a combined display and dispensing carton, substantially as shown.

EDWARD J. NOVAK.
